UNITED STATES PATENT OFFICE.

JOHN B. CALVERT, OF GUTHRIE, OKLAHOMA TERRITORY.

SELF-CLOSING INK-WELL.

SPECIFICATION forming part of Letters Patent No. 739,289, dated September 22, 1903.

Application filed June 24, 1903. Serial No. 162,961. (No model.)

To all whom it may concern:

Be it known that I, JOHN B. CALVERT, a citizen of the United States, residing at Guthrie, in the county of Logan, Oklahoma Territory, have invented new and useful Improvements in Self-Closing Ink-Well, of which the following is a specification.

This invention relates to self-closing ink-wells, and has for its object the production of a simple and efficient appliance of this character constructed to be air-tight in closed condition and which is readily opened by pressure from the pen-holding hand of the user.

The nature of the invention will be readily comprehended, reference being had to the following detailed description and to the accompanying drawings, illustrating the invention in its preferred form of embodiment, it being understood that various modifications may be made therein without departing from the spirit of invention defined by the concluding claims.

In the drawings, Figure 1 is a top plan view of a self-closing ink-well embodying the invention. Fig. 2 is a vertical sectional view of the ink-well in closed condition. Fig. 3 is a similar view with the ink-well opened.

Referring to the drawings by numerals, 1 designates the base of the ink-well, on which 20 are supported two wells 2 for ink, although a single well may be employed. Each well has a sliding cover 3, which in closing position effectually seals the well against admission of air and which in opening position rests 35 on a bracket-plate 4, supported from the base by an arm 5 and resting on the top of the well at the rear of the ink-chamber.

Pivoted by means of an eye 6 on the rear portion of the base is a lever having an upwardly-extending arm 7, connected by a link 8 with the cover 3. Where two ink-wells are provided, the link is of T form, as shown, attachment with the covers being made at the ends of the head 9. On the link is a pen and pencil rack 10 in the form of a spirally-coiled wire. The lever is preferably constructed from a single length of stout wire, and the outer end of the link 8 is preferably bent around a lateral bend of the arm 7, and likewise the lever at its pivotal point is laterally bent, said bent portion occupying the eye 6. The other arm, 11, of the lever depends from

the pivotal point at an angle to the arm 7, and engaging said arm 11 is a lever 12, having its fulcrum on a rod 13, extending crosswise of 55 the base.

14 denotes a plate of U form loosely attached at its ends to the rear portion of the base and extending, as shown in Fig. 1, about the ink well or wells. Secured to and depending from 60 the forward or free end of the plate is a link 15, having a lower hook-shaped end 16, engaging the upturned end 17 of the lever 12. A coiled spring 18 is attached at its ends, respectively, to the base and the link 8. 65

In operation pressure by the hand of the user on the upper side of the plate 14 depresses the latter, and through the medium of the link 15 and lever 12 the lever 7 11 is rocked to the position shown in Fig. 3. Such movement of the lever is communicated by the link 8 to the cover or covers, the latter being carried rearwardly to uncover the ink-wells and in such position are supported by the bracket-plate 4. In the movement of the parts to uncover the ink-wells the spring 18 is expanded, and the pressure being removed from the plate 14 said spring operates to retract the parts and return the covers to closing position. 70 75

I claim as my invention—

1. A self-closing ink-well, consisting of a well, a slidable cover therefor, a U-shaped pivoted plate partly encircling the well, a pivoted lever beneath the well and having link connection with the plate, a pivoted lever at 85 the rear of the well having link connection at its upper end with said cover and having its lower end in engagement with the aforesaid lever.

2. A self-closing ink-well, consisting of a well, a slidable cover therefor, a U-shaped pivoted plate, a lever having link connection with the plate, a lever arranged to be moved by the aforesaid lever, a link connecting the last-named lever with the cover, a spring connected to the link, and a pen and pencil rack carried by said link. 90 95

In testimony whereof I have signed my name to this specification in the presence of two subscribing witnesses.

JOHN B. CALVERT.
